UNITED STATES PATENT OFFICE.

ARTHUR L. STEVENS, OF CHICAGO, ILLINOIS.

REGENERATIVE FURNACE FOR ANNEALING AND LIKE PURPOSES.

1,219,500.

Specification of Letters Patent. Patented Mar. 20, 1917.

Application filed September 10, 1912. Serial No. 719,529.

To all whom it may concern:

Be it known that I, ARTHUR L. STEVENS, a citizen of the United States, residing at Chicago, in the county of Cook and State of Illinois, have invented certain new and useful Improvements in Regenerative Furnaces for Annealing and like Purposes, of which the following is a specification.

The invention relates to regenerative furnaces and particularly to furnaces for annealing or like purposes.

One of the objects of the invention is to provide a furnace of this character which will be very compact thereby economizing floor space, decreasing cost of construction and minimizing heat losses by radiation.

A further object is to provide a furnace in which the annealing is done by radiation without direct impingement of the flame on the articles treated.

A further object is to provide certain arrangements of the flues and the instrumentalities employed for introducing the fuel into the heating chamber whereby all of the articles treated may be subjected to a uniform temperature.

A further object is to provide a furnace which may be adapted, by making slight changes in certain structures, for the use of either gas or oil as a fuel.

A further object is to provide a furnace structure which will be very strong and durable, the construction in this respect contemplating the practical elimination of arches and an arrangement of the movable hearth whereby the weight of the hearth and the articles carried thereby is transmitted directly to a foundation without exerting any stress on the brick work of the furnace.

The invention has for a further object to provide certain novel constructions and devices for reversing the circulation through the regenerators and heating chamber.

The invention has for a further object to provide a furnace having the new and improved features and consisting of the novel arrangements, combinations and constructions shown in the drawings hereto annexed and which will be more fully described and claimed in the following specification.

The accompanying drawings show a pre-

ferred form of annealing furnace embodying the principles of the invention.

In these drawings,

Figure 1 is a front elevation with the foundation shown in section;

Fig. 2, a longitudinal sectional view taken on line 2-2 of Fig. 1, looking in the direction of the arrows;

Fig. 3, a sectional plan taken on line 3-3 of Fig. 2;

Fig. 4, a cross-sectional view on line 4-4 of Fig. 5, looking in the direction of the arrows;

Fig. 5, a longitudinal sectional view on line 5-5 of Fig. 4, looking in the direction of the arrows;

Fig. 6, a sectional plan taken on line 6-6 of Fig. 5;

Fig. 7, a cross-sectional view on line 7-7 of Fig. 5, looking in the direction of the arrows;

Fig. 8, a similar view on line 8-8 of Fig. 3;

Fig. 9, a detail sectional view illustrating a modification adapting the furnace for the use of gas as a fuel instead of oil; and

Fig. 10 is a sectional view taken on line 10-10 of Fig. 9, looking in the direction of the arrows.

Like characters of reference designate like parts in the several figures of the drawings.

The furnace structure is made up of brick work preferably built upon a cement foundation 25 and supported and reinforced by a structural steel frame 26. The furnace structure consists of side walls 27, a back wall 28 and an arched roof 29, the thrust of which latter is taken by the structural steel frame 26, the arch being supported on angle irons 30 secured to the steel frame. The front end of the furnace is open. Within the furnace are rails 31 laid on ties 32 on the cement foundation 25. A truck 33 runs on the rails 31 and the platform 34 of this truck, which is of refractory material, forms the hearth of the furnace. The opening in the front of the furnace above the hearth is closed by suitable doors 35 to which are attached cables 36 passing over sheaves 37 on the steel framing of the furnace. Any suitable mechanism may be employed for raising and lowering the doors. Seals are pro-

vided for preventing the escape of heat from the heating chamber around the sides of the truck, the seals consisting of troughs 39 filled with sand, into which project flanges 40 on the truck.

5 At the sides of the heating chamber designated 38 are bridge walls 41, 41' spaced away from the side walls of the furnace so as to provide vertical combustion spaces 42, 42'. Beneath the bridge walls and combustion spaces at opposite sides of the furnace are series of regenerators filled with the usual checker work, which regenerators are designated 43, 43'. The regenerators 43 on one side of the furnace are connected together by a flue 44 extending from end to end of the furnace under said regenerators, the regenerators 43' on the other side of the furnace being similarly connected, one with another, by a flue 44'. The regenerators of each series are separated from one another by transverse partition walls 45 which extend from the outer side walls 27 of the furnace back to the inner walls 46. Each regenerator communicates with the combustion space, 42 or 42' as the case may be, by a flue 47. These distributing flues are arranged in pairs, the flues of each pair converging or being inclined one toward the other at the top. The combustion spaces 42, 42' are each divided into a number of separate spaces or flues by means of partition walls 48 built upon the partition walls 45. One pair of flues 47 communicates with each of the subdivisions of the combustion spaces 42, 42'.

40 The side walls of the furnace are formed with recesses 49 which extend back under the combustion spaces between the flues of each pair of flues 47. The brick work under the combustion spaces is formed with flaring openings 50, and burners 51, 51' are located in the spaces 49 directly beneath these openings. Any suitable form of gas or oil burner might be used. I have shown oil burners such as that which forms the subject-matter of my copending application Serial No. 719,527, filed September 10, 1912, but in view of the fact that burners of various types might be used in place of this preferred burner, it will not be necessary to describe the latter in detail.

45 As stated, the furnace might be fired with gas, very slight structural changes being necessary to convert it from an oil to a gas consuming furnace. The necessary changes are shown in Figs. 9 and 10. A larger opening is made in the brick work between the recess 49 and the combustion space 42 and baffle bricks 52 are placed crosswise of each other over this opening. The front of the recess 49 is closed up as indicated at 53 and gas is admitted to the recess through a nozzle 54 leading from the gas main 55.

50 In order to insure a proper distribution

of air passing in and out of the heating chamber through the flues 47 and thereby provide for heating the annealing chamber uniformly from one end to the other, the several flues 47 are provided with brick dampers 56 which slide through slots in the side walls of the furnace and in grooves 57 (Fig. 5) in the brick work defining said flues. The dampers 56 may be adjusted so that the distribution of incoming air at one side of the furnace, and similarly the outgoing products of combustion on the other side of the furnace, will be equalized for the several flues. Without this equalizing means the circulation would be likely to short-circuit through one end of the furnace.

55 The flues 44, 44' extending under the regenerators on opposite sides of the furnace are connected by a cross flue 58 at the back of the furnace. The stack 59 leads from the middle of this flue.

60 A double-acting valve is arranged at each end of the cross flue 58. Each of these devices is adapted at one relative position of its operative parts to open the regenerator with which it is associated to the atmosphere so that fresh air may enter same, and at the same time close communication between said regenerator and the stack; and at another relative position of said parts to close the fresh air intake and put the regenerator in communication with the stack. The valves are identical and may be constructed as follows: 60 (having reference to the left hand valve in Fig. 8) designates a tubular element which slides through a cover plate 61 arranged over an opening 62 in the brick work 63 in which flue 58 is formed. The tubular element is provided at the bottom with a valve 64 adapted to engage a seat 65 surrounding an opening 66 between the flue 44 and the cross flue 58. The tubular element is suspended at the end of a rod 67 which is attached to a cable 68 passing over sheaves 69, 70, 71, 72 to the valve on the other side of the furnace. Slidably mounted in a framework 73 is a sleeve 74 through which passes the rod 67, the sleeve being threaded at its upper end for a nut 75 having, for convenience of manipulation, the hand wheel 76. On the end of the sleeve is a disk valve 77 adapted to close the open end of the tubular element 60 when the latter is raised. The function of nut 75 is to adjustably position the valve 77 with respect to the end of the tubular element 60 so as to vary the effective size of the air intake provided when the tubular element is in its lower position in engagement with seat 65. As the sleeve 74 is slidable, the valve 77 will travel with the tubular element 60 if its initial position with respect to the end of the tubular element requires it.

65 For convenience in describing the opera-

70

tion of the valves, the reference character 60' is used to designate the tubular valve element on the other side of the furnace from the valve just described. The other 5 parts of these two mechanisms, which are identical, are given the same reference numbers in the drawings. It will be understood that the arrangement is such that when the tubular element 60 is in its upper position 10 the element 60' is in the lower position and vice versa.

I do not lay claim herein to the valve mechanism just described, taken by itself, as the same forms the subject matter of my 15 copending application Serial No. 719,530, filed September 10, 1912.

The operation of the furnace above described is as follows: Assuming the valves 60, 60' to be in the positions shown in Fig. 8, fresh air enters the regenerators 43 at one 20 side of the furnace through the tubular valve element 60 and flue 44 and after being preheated in the regenerators (which have received heat in the previous cycle) passes 25 into the combustion spaces 42 where it is mixed with the oil from burners 51, or gas from gas pipes 54 as the case may be. Combustion takes place in the spaces 42, the flames being directed upwardly against the 30 roof of the furnace. The flames are projected across the heating chamber with a reverberatory action against the roof and are drawn down by the stack draft through the combustion spaces 42', into the regenerators 43', and thence through the flue 35 44' to the stack 59, the valve element 60' (at the right hand side of Fig. 8) being raised so as to put the flue 44' in communication with the cross flue 58 and close the 40 air intake on this side of the furnace.

To equalize the temperature in the heating chamber the bridge walls are preferably formed with the openings 78. The combustion takes place in the upper part of the 45 heating chamber above the bridge walls and hence there is no direct impingement of the flames upon the work on the hearth 34. The articles treated are heated by radiation.

The arrangement of a number of separate 50 regenerators at each side of the furnace tends to equalize the temperature of the incoming air and distribute the same uniformly from one end of the furnace to the other. Perfectly equalized distribution may be obtained by a proper adjustment of the dampers 56. This insures a uniform temperature in the furnace from end to end so that the articles treated are heated uniformly.

The circulation through the regenerators 60 and through the heating chamber is reversed by raising the tubular element 60 and lowering the tubular element 60' which may be done simultaneously. Fresh air is now taken into the furnace through flue 44' and 65 the regenerators 43'. Fuel is now supplied

to the furnace on this side, the supply on the other side being cut off. The draft across the heating chamber is from bridge wall 41' to bridge wall 41. The products of combustion pass down through the spaces 70 42 into the regenerators 43 and out through flue 44 to the stack, the valve element 60 standing away from its seat and being closed at the top so as to put the flue 44 in communication with the cross flue 58 and 75 close the fresh air intake.

From the point of view of structure it will be seen that the furnace is very compact. It occupies but little floor space. This is an advantage in itself and also minimizes heat losses by radiation. The truck 80 33 and its load is borne directly by the cement foundation 25. It exerts no stress against the furnace structure. The use of arches is almost entirely eliminated. The 85 only arch is the roof arch 29 and the thrust of this arch is taken by the steel frame of the furnace. In forming the flues 44, 44', the distributing flues 47 and the regenerators, the bricks are corbeled as shown so as 90 to avoid the use of arches. This makes the furnace structure very strong and durable.

The furnace can be readily adapted to the use of either oil or gas as a fuel, the modification in structure necessary to make the 95 change from one fuel to the other being very slight.

While I have described my invention in certain preferred embodiments, it will be understood that modifications might be 100 made without departure from the invention. Therefore, I do not wish to be understood as limiting the invention to all of the particulars of construction and arrangements shown and described.

I claim:

1. In a furnace for annealing, or like purposes, the combination with means constituting a heating chamber, of bridge walls in said heating chamber extending above 110 the hearth of the chamber and spaced from the side walls thereof so as to provide combustion spaces, and a plurality of separate regenerators arranged lengthwise of the furnace on each side having flues communicating with said combustion spaces.

2. In a furnace for annealing, or like purposes, the combination with means constituting a heating chamber, of bridge walls in said heating chamber extending above 120 the hearth of the chamber and spaced from the side walls thereof so as to provide combustion spaces, and a plurality of separate regenerators arranged under each combustion space, and flues connecting said regenerators with said combustion spaces.

3. In a furnace for annealing, or like purposes, the combination with means constituting a heating chamber, of bridge walls in said heating chamber spaced from the side 130

4. walls thereof so as to provide combustion spaces, and a plurality of separate regenerators arranged under each combustion space, and pairs of flues leading from said regenerators to the combustion spaces, the flues of each pair inclining toward each other.
5. In a furnace for annealing, or like purposes, the combination with means constituting a heating chamber, of bridge walls in said heating chamber spaced from the side walls thereof so as to provide combustion spaces, and a plurality of separate regenerators arranged under each combustion space, pairs of flues leading from said regenerators to the combustion spaces, the flues of each pair inclining toward each other, and transverse partition walls in said spaces between the pairs of flues.
6. In a furnace for annealing, or like purposes, the combination with means constituting a heating chamber, of bridge walls in said heating chamber spaced from the side walls thereof so as to provide combustion spaces, a plurality of separate regenerators arranged under each combustion space, pairs of flues leading from said regenerators to the combustion spaces, the flues of each pair inclining toward each other, and means for introducing fuel into the combustion spaces between the flues of each pair of flues.
7. In a furnace for annealing, or like purposes, the combination with means constituting a heating chamber, of bridge walls in said heating chamber extending above the hearth of the chamber and spaced from the side walls thereof so as to provide combustion spaces, a plurality of separate regenerators arranged lengthwise of the furnace on each side having flues communicating with said combustion spaces, and a flue extending under and connecting together the regenerators on each side of the furnace.
8. In a furnace for annealing, or like purposes, the combination with means constituting a heating chamber, of bridge walls in said heating chamber extending above the hearth of the chamber and spaced from the side walls thereof so as to provide combustion spaces, a plurality of separate regenerators arranged lengthwise of the furnace on each side having flues communicating with said combustion spaces, a flue extending under and connecting together the regenerators on each side of the furnace, and means for reversing the draft through said regenerators and heating chamber.
9. In a furnace for annealing, or like purposes, the combination with means constituting a heating chamber, of bridge walls in said heating chamber extending above the hearth of the chamber and spaced from the side walls thereof so as to provide combustion spaces, regenerators arranged under said combustion spaces, and distributing flues connecting the regenerators with said combustion spaces.
10. In a furnace for annealing, or like purposes, the combination with means constituting a heating chamber, of bridge walls in said heating chamber extending above the hearth of the chamber and spaced from the side walls thereof so as to provide combustion spaces, regenerators arranged under said combustion spaces, distributing flues connecting the regenerators with said combustion spaces, and dampers slidably mounted in the side walls of the furnace to equalize the inflow and outflow through said distributing flues.
11. In a furnace for annealing, or like purposes, the combination with means constituting a heating chamber, of bridge walls in said heating chamber extending above the hearth of the chamber and spaced from the side walls thereof so as to provide combustion spaces, regenerators arranged under said combustion spaces and communicating therewith, a flue connecting the regenerators on one side with those on the other, a stack opening out of said flue between the regenerators, and a valve mechanism interposed between each regenerator and the stack adapted in one position to open the air intake to the regenerator and close communication between the regenerator and the stack and in another position to close said air intake and open communication between the regenerator and the stack.
12. In a furnace for annealing, or like purposes, the combination with means constituting a heating chamber, of bridge walls in said heating chamber extending above the hearth of the chamber and spaced from the side walls thereof so as to provide combustion spaces, regenerators arranged under said combustion spaces and communicating therewith, a flue connecting the regenerators on one side with those on the other, a stack opening out of said flue between the regenerators, and a valve mechanism interposed between each regenerator and the stack adapted in one position to open the air intake to the regenerator and close communication between the regenerator and the stack and in another position to close said air intake and open communication between the regenerator and the stack, said mechanism comprising means for varying the effective size of said air intake.
13. In a furnace for annealing, or like purposes, the combination with a foundation, of a furnace supported on the foundation open at one end, a truck adapted to enter the open end of the furnace, a track for said truck supported directly on said foundation, a door closing the open end of the furnace above said truck, bridge walls within said furnace, regenerators arranged under said combustion spaces, and distributing flues connecting the regenerators with said combustion spaces.

under the bridge walls, distributing flues between the regenerators and the spaces back of the bridge walls, a flue connecting the regenerators on one side of the furnace with these on the other, a stack leading from said connecting flue, and valve mechanism for reversing the circulation through said furnace and regenerators.

13. In a furnace for annealing or like purposes 10 the combination with means constituting a heating chamber, of bridge walls in said heating chamber extending above the hearth of the chamber and spaced from the side walls thereof so as to provide combustion spaces, and flues for creating an upward draft in said spaces; said heating chamber including a roof arched across the

chamber from one of said side walls to the other.

14. In a furnace for annealing or like purposes 20 the combination with means constituting a heating chamber, of bridge walls in said heating chamber extending above the bed of the chamber substantially half-way to the roof thereof and spaced from the side walls thereof so as to provide combustion spaces, and flues for creating an upward draft in said spaces; said heating chamber including a roof arched across the chamber from one of said side walls to the other.
